HIS ATTORNEY.

UNITED STATES PATENT OFFICE.

ERNEST G. GOODWIN, OF PELHAM, NEW YORK, ASSIGNOR TO STANDARD COUPLER COMPANY, OF NEW YORK, N. Y., A CORPORATION OF NEW JERSEY.

WEAR PLATE.

Application filed June 29, 1926. Serial No. 119,396.

This invention relates to draft gears and has for its object the provision of means for lessening the expense of such gears by providing detachable wear plates.

5 A gear of the type shown, except that the wear plate and barrel are integral, is a very satisfactory piece of car equipment and is at the present time well-known and in use, while the wedges themselves are relatively inexpensive. The barrel is a huge steel casting that is relatively quite expensive. As the only part of the barrel that wears is the box, by making the box detachable a considerable saving may be had by prolonging the life of 10 the gear after the box is worn, making it unnecessary to scrap the large steel casting. The wear plate illustrated is of special ribbed formation, the rib and the lug relatively 15 strengthening each other and adding very materially to the life of the plate.

In the drawings:—

Figure 1 is a side view of the device partly in central section and

20 Figure 2 is a front elevation with the lower wear plate in place but with the upper wear plate removed so as to show the hole or recess in the barrel.

The gear shown except for the wear plates follows general practice consisting of a spring 25 barrel 10 having a removable rear end plate 11 and spring 12. The front walls 13 outwardly diverge and have a recess 14 which may be a hole extending entirely thru the casting as shown.

30 A wear plate 16 fits snugly each sloping wall 13 and has an integral lug 17 fitting snugly the recess or hole 14 so as to hold the wear plate in place. On the inner or concave side 18 of the wear plate is a rib 19 which does not extend the entire length of the wear plate from front to back thus providing a shoulder 35 which engages a shoulder on the side wedge 20 formed by the grooving of the proximate face as indicated at 21. The rib and groove 40 thus form a limiting means preventing the side wedges from moving out of the barrel as they would otherwise do under urge of the center wedge 22 which is pressed outwardly or forwardly by the spring 12.

45 The operation of the device is believed to be apparent. The wear occurs between the

sloping faces of the center wedge and the corresponding faces of the side wedges and between proximate faces of the side wedges and the plates, the latter forming the so-called box of the spring barrel. When any of the wedges become worn to a given extent they are scrapped but instead of scrapping the large and expensive barrel casting, as has been the past practice, the wear plates are 55 merely replaced with similar elements. Obviously the construction is such that the wedges in the wear plate type of barrel are identical in size with the similar elements in the standard equipment so that a standard 60 stock set of repair parts would be sufficient to repair either the old or the new gears, including of course, with the new gears, the 65 requisite number of wear plates.

What I claim is:—

1. In a draft gear, a spring barrel having two outwardly diverging walls at the open end, each wall having a recess therein, a pair of wear plates each having a lug fitting one of said recesses, a center wedge, a spring engaging said wedge and the closed end of said barrel, a plurality of side wedges in engagement with said center wedge each having a groove extending part-way only of its outer friction face, and a guiding rib on each plate 80 opposite the lug for engaging said grooves to guide and limit movement of said side wedges.

2. The device of claim 1 in which the plates are curved on their ribbed and lugged faces. 85

3. A wear plate for a draft gear having a concave wearing face to engage a wedge and a convex face to engage the front end of a spring barrel, a lug extending from the convex face, and a rib extending from the concave face, the centerline of the lug passing centrally thru the centerline of the rib. 90

4. A wear plate for a draft gear having an inner wearing face to engage a wedge and an outer face to engage the front end of a spring 95 barrel, a lug extending from the outer face, and a rib extending from the inner face, the centerline of the lug passing centrally thru the centerline of the rib.

In testimony whereof I affix my signature.

ERNEST G. GOODWIN.
